J. H. G. LUTZ

COMBINED FAUCET AND DRINKING FOUNTAIN

Filed Aug. 20, 1921

UNITED STATES PATENT OFFICE.

JOHN H. G. LUTZ, OF CHICAGO, ILLINOIS, ASSIGNOR OF ONE-HALF TO WILLIAM F. J. LUTZ, OF CHICAGO, ILLINOIS.

COMBINED FAUCET AND DRINKING FOUNTAIN.

Application filed August 20, 1921. Serial No. 493,807.

To all whom it may concern:

Be it known that I, JOHN H. G. LUTZ, a citizen of the United States, and a resident of Chicago, in the county of Cook and State 5 of Illinois, have invented certain new and useful Improvements in Combined Faucets and Drinking Fountains; and I do hereby declare that the following is a full, clear, and exact description thereof, reference being had to the accompanying drawings and 10 to the characters of reference marked thereon, which form a part of this specification.

This invention relates to a novel combination faucet and drinking fountain cup 15 which is adapted for household and other uses where a constant use of a faucet is required and where it is convenient and desirable to combine in a single structure a so-called drinking or bubbling fountain and 20 valve, the water supply of which is received from the same connection to the water pipe.

Among the objects of the invention is 25 to provide in a combination of this character a very simple, readily made and attractive structure which serves the double purpose of an ordinary faucet and drinking fountain.

A further object of the invention is 30 to provide in a combination of this character a fitting which is connected to the supply source, and of a shape to receive the valved faucet portion and the drinking fountain portion, the fitting in this instance being 35 a T-fitting, the main or body portion of which constitutes a through conduit for the faucet, and the upstanding portion of which constitutes a conduit for the bubbling fountain.

40 A further object of the invention is to provide in a structure of this character a bubbling fountain in which the pipe which carries the drinking cup, and which is made hollow for the purpose of conducting water thereto, constitutes also the means for actuating the valve which controls the flow 45 of water to the drinking cup.

Other objects of the invention are to 50 further improve and simplify structures of this character, and the invention consists in the combination and arrangement of the elements shown in the drawings and described in the specification, and is pointed out in the appended claims.

In said drawings:

Figure 1 is a side elevation of a combined 55 faucet and drinking fountain embodying my invention.

Figure 2 is a section on the line 2—2 of 60 Figure 1, with the drinking fountain elements shown in position to close the valve of the drinking fountain.

Figure 3 is a cross section on the line 3—3 of Figure 2.

As shown in said drawings, 10 designates 65 the outlet pipe from the water system, which extends through the wall 11 and, in the construction shown, is common to both the faucet and drinking fountain. 12 designates a T-fitting or connection 70 comprising a horizontal portion 13 and a vertical or rising portion 14. Said horizontal portion of the T-fitting is connected at one end by a threaded joint to the outlet 10, and is connected at its other 75 end, as by a screw thread, to a draw-off spout 15 and valve chamber 16 in which is located a valve for controlling the faucet that is actuated in a familiar manner by a stem 17 provided with a hand piece 18. 80

19 designates an upstanding shell that is provided at its lower end with a reduced, externally threaded part 20 which enters the vertical branch 14 of the T-fitting and is threaded thereto in the manner shown in 85 Figure 2. Said shell 19 is formed with an interior valve chamber 21, connected with the body portion of the T-fitting by a short passage or conduit 22. Said conduit 22 terminates in a seat flange 23 surrounding a 90 port 23'.

24 designates a valve which engages a seat on the said flange 23 to close the water passage or conduit to the shell 19. In the present instance the valve has the form 95 of a ball which is pressed to its seat by a stem 25. Said stem, as shown, has a rather coarse pitch thread 26 to engage an internal threaded passage disposed axially of the shell and in line with the port 23' 100 surrounded by the seat flange. The said stem is formed at its lower end to provide a downwardly opening concave bearing end or cup 27 of an internal shape to fit the perimeter of the ball valve.

The said stem 25 is reduced above its screw thread 26, and extends through a stuffing box of any suitable character. As 105

herein shown, the stuffing box comprises a gland nut 28 which has a cylindric skirt portion 29 that fits closely within the cylindric upper end 30 of the shell 19. Said skirt portion is adapted to bear at its lower end against a packing washer 31, which surrounds the stem 25 and is compressed between said lower end of the skirt portion and a shoulder 32 formed between the smaller screw-threaded portion of the shell 19 and the interiorly cylindric portion thereabove to receive said skirt portion of the nut. The nut is provided exterior to said skirt portion with an annular 10 interiorly threaded flange 33, which is separated therefrom by an annular space 34 to receive an exteriorly screw-threaded, reduced, upstanding terminal 35 of the shell. With this construction, it will be observed 15 that the threaded connection of the nut with the shell acts through the skirt portion 29 to bring pressure on the washer 31 to force it closely against the stem which extends therethrough to produce a water tight joint.

20 The said valve stem is principally hollow. It is open at its upper end 36 and communicates at its lower end through cross openings 37 with the valve chamber 21.

30 38 designates a hollow arm which is fitted, as by an elbow 39, to the terminal 36 of the tubular valve stem, and 40 designates an upwardly opening cup which is supported on the outer end of said tubular arm 38 and into which the water is discharged for 35 drinking purposes. The said hollow arm 38 is fixedly connected to the upper terminal 36 of the valve stem, and thereby constitutes means whereby the valve stem can be turned on its axis, the threaded connection of said stem with the shell moving the same axially during such turning movement of the cup supporting arm. When the arm 38 is turned to the position shown 40 in Figure 1, the stem 25 is lifted by said screw-threaded connection, thus permitting the water pressure beneath the ball valve to lift the valve away from its seat, as indicated in Figure 1, and at this time there is a free passage for the flow of water upwardly through the vertical arm 14 of the T, into the valve chamber, through the cross 45 passages or ports 37, and thence through the bores of the stem 36 and arm 38 to the cup.

50 55 As herein shown, and preferably, the said controlling valve for the drinking fountain is adapted to be opened at a time when the arm 38 is turned outwardly in a position directly over the valve chamber and spout of the faucet proper, and is adapted to be closed when the arm 38 and the cup 40 is turned 90 degrees toward wall 11, as indicated in Figure 2, the hand of the screw threads being adapted for this purpose.

60 65 Preferably, and as shown, the said arm

38 and its cup are adapted to be automatically swung into position for closing the drinking fountain controlling valve so as to thereby avoid unnecessary waste of water by carelessly allowing said parts to remain 70 in position to permit water to flow therethrough. Such automatic closing of the drinking fountain valve and swinging of the arm 38 and cup 40 out of operating position can be effected by a torsional 75 spiral spring 41, which surrounds the valve stem within an annular space therebetween and the skirt portion 29 to the nut or gland 28. One end of said spring is fixed to the upper end of the valve stem, and the other end thereof is fixed or anchored in any suitable manner to a fixed part of the structure, as the gland nut. With this construction, therefore, when the drinking fountain is swung outwardly in operative position, or over the faucet spout, it places the torsional spring 41 under tension and thereby stores power in said spring to automatically return the parts.

80 85 The pressure of the water beneath the ball valve 24 acts to lift said valve when the stem is moved upwardly in turning it in a direction to axially lift it, so as to permit free flow of water outwardly through the hollow stem and the arm or neck 38 to the 90 cup. The passage of the water past the ball valve has the effect to shift the valve relatively to its seat so that when the valve stem is lowered and the valve is pressed on its seat, it will engage the seat and the cup portion 27 of the stem, and thus avoid continual wear on the ball valve at certain 95 definite areas.

100 105 From what has been said, it is obvious that the combined structure of the faucet and drinking fountain can be made up by a few readily machined parts. The individual parts are easily constructed and may be readily assembled and the combined structure, when installed, produces a very 110 attractive device. For the purpose of compactness, it is preferable to curve downwardly the tubular arm 38 in the general form of a goose neck.

115 120 It will be understood that the structural details are capable of some variations within the spirit and scope of the claims hereto appended, and that the invention is not limited to the particular details illustrated, except as hereinafter specifically claimed and as imposed by the prior art.

I claim as my invention.

125 130 1. In a combined faucet and drinking fountain a tubular T-shaped fitting adapted for communication with a water supply and with a valved spout, the intermediate portion of the T extending upwardly, a shell supported thereby and communicating with the interior of the T, said shell being provided with an interior port, a valve to con-

trol the port, a hollow valve controlling stem threaded to the shell, and a hollow arm fixed to the upper end of the stem and communicating therewith and carrying at its 5 outer end a drinking cup,

2. In a combined faucet and drinking fountain, a tubular T-fitting whose main body is adapted to communicate with a water inlet and with a valved draw-off 10 spout, a valve casing connected to the vertical branch of said fitting and provided with a port, a valve controlling said port, a stem threaded in the shell of said casing for movement towards and from the port to 15 actuate said valve, said valve stem being hollow, and a hollow arm connected to the hollow valve stem and carrying at its other end a drinking cup, said drinking fountain

valve being opened and closed by angular movement of said arm to turn the valve 20 stem.

3. In a combined faucet and drinking fountain, a tubular T-fitting whose main body is adapted for connection at one end with a water inlet and at its other end with 25 a valved spout, said fountain comprising a conduit which is supported on and extends upwardly from the vertical branch of said fitting, a water controlling valve in said conduit and a hollow stem communicating 30 with the outlet of said fountain and adapted to control the fountain valve.

In witness whereof I claim the foregoing as my invention, I hereunto append my signature this 17th day of August, 1921.

JOHN H. G. LUTZ.
